RECEPTACLE BASE

Walter J. Gleisner, Chicago, Ill., assignor to W. C. Ritchie and Company, Chicago, Ill., a corporation of Illinois

Application November 8, 1945, Serial No. 627,356

7 Claims. (Cl. 229—5.5)

1

The current invention pertains to certain novel features of advantageous structure and resulting beneficial properties in the bases or bottoms of receptacles or containers, such, for instance, as those used for accommodating toilet preparations, as for example, face-powder.

It is not new to make boxes holding powder-containing drums with frangible or rupturable tops which are broken through when the powder contents are to be used for the first time.

Such open-bottom drums housed in their open-bottom covers are ordinarily filled while they are upside down with the powder to be marketed and then the bottom of the drum is snapped or forced into place closing the bottom thereof and having an extended marginal portion underlying the lower edge of the removable cover when the box is completed and is right side up.

Such filled containers are subjected to various conditions which tend to detrimentally affect them or their contents.

Such applied bottom must seal its opening tightly under all conditions of temperature, moisture, careless handling, etc. This bottom must not shrink or expand any appreciable amount; it must retain its original size, and in some instances the matter of transmission of heat or cold through the bottom to the contents may be a significant factor.

For example, if one such filled container is displayed in the sunshine in a store window for an extended period, it is likely to shrink or otherwise be modified so that it does not seal tightly and the contents of the receptacle may be spoiled or detrimentally affected or spilled.

A plastic bottom could readily be modified under such conditions as to make it undesirable.

According to the present invention, the novel and improved bottom is made in a special manner to provide a resulting structure which is not subject to the indicated and other weaknesses and defects which render them unsatisfactory in one or more respects.

In order that those acquainted and skilled in this art may understand this invention, both from structural and operative standpoints, a present preferred type of bottom and its method of production have been fully illustrated in the accompanying drawing forming a part of this specification and to which reference should be had in connection with the following detailed description thereof.

In this drawing:

Figures 1 and 2 illustrate the original metal disc employed;

2

Figures 3 and 4 portray the first step in the process of making the bottom;

Figures 5 and 6 depict the second step in the method of forming the metal member of the bottom:

Figure 7 shows the pasteboard or comparable disc;

Figure 8 presents the metal member and the pasteboard disc united together;

Figure 9 reveals the application of a second pasteboard disc inside of the bottom;

Figure 10 is a section through the completed box or container; and

Figure 11 is an enlarged, fragmentary section of a portion of the box to more clearly present its details of construction.

In accordance with the new procedure of the present invention a flat, round, thin, metal disc

21 of proper diameter, as shown in Figures 1 and 20 2, by means of suitable companion dies, is shaped into inverted dish-form 22, Figures 3 and 4, with a marginal depending rim 23 and an outstanding, terminal, circular flange 24, the main body of such member having a series of circularly-disposed, spaced-apart, small apertures 25, 25 concentric with the element itself, and the metal which formed the apertures having been forced down to provide around each such hole four, depending, sharp-pointed, downward-flaring prongs

30 26, 26.

Thereafter, the whole main body or top of the disc is pressed or forced down inside of the rim 23 into the plane of the marginal flange 24 as depicted in Figures 5 and 6, thereby making the new circular rim 27 of double thickness and undercut on its outer face and sloping upwardly outwardly on its inner surface.

Thereupon, Figures 6 and 7, such formed metal member 28 with its depending, sharp-pointed, flaring prongs is placed coaxially on the top surface of a somewhat-larger, flat, round, pasteboard or comparable disc 29 and then pressed or forced down into firm engagement with such surface, the prongs 26, by reason of their outwardly-spreading disposition entering and penetrating the material of the disc in analogous directions, thus binding the pasteboard disc 29 firmly to the underside of the metal member 28.

Then another cardboard or similar disc 31 is applied to and cemented to the top face of the metal member and is of a size substantially the same as that inside of the rim 27 so that all of the apertures 25 are closed and the bottom presents an attractive appearance.

55 Subsequently, while the powder-filled drum 32

is in its encasing cover 33 and both are upside down so that their bottoms are open (not so shown) the now completed novel and improved bottom is snapped onto and partly into the open bottom of the drum, the circular rim or bead 27 of the metal member of the bottom extending in beyond the internal, curled, marginal bead 34 of the drum and being permanently held and maintained in powder-tight relation therewith from then on.

The one outstanding, highly desirable characteristic of this new type of bottom is that it cannot change size or become deformed because of its metallic properties.

The cover of this container may have a paper covering of artistic appearance and the exposed edge of the bottom below the cover may be also supplied with an attractive covering whereby the container as a whole can be extremely pleasing in appearance.

Those acquainted with this art and industry will readily understand that the present invention is not necessarily confined to the exact and precise details of structure set forth and that reasonable changes may be availed of both as to procedure and structure without departure from the heart and essence of the invention as defined by the appended claims.

I claim:

1. In an undercut bottom for application to a receptacle having an internal marginal bead around its bottom mouth of a size to fit firmly over an undercut rim on such bottom to hold the latter to the receptacle, the novel combination of an upper metal-member and a lower fibrous-element, said member having an upstand-

ing integral externally-undercut rim and a plurality of depending, integral, flaring prongs embedded in said lower element thereby fastening said upper member and lower element permanently together.

2. The novel combination in a receptacle bottom set forth in claim 1, in which said metal rim is of double-thickness.

3. The novel combination in a receptacle bottom set forth in claim 1, in which said upstanding undercut rim is inwardly away from the periphery of such metal member.

4. The novel combination in a receptacle bottom set forth in claim 1, in which said prongs are inwardly of the metal member from said upstanding rim.

5. The novel combination in a receptacle bottom set forth in claim 1, in which said lower fibrous-element is sufficiently large to underlie the cover of the receptacle.

6. The novel combination in a receptacle bottom set forth in claim 1, in which said prongs are divided into groups, each group surrounding an aperture through the metal member.

7. The novel combination in a receptacle bottom set forth in claim 1, in which said member and element are circular and concentric, in which said element is larger than said member, in which said rim is of double-thickness and circular, and in which said prongs are divided into a circular series of groups, each group surrounding an aperture through the member and said prongs and apertures are concentric with the metal member and are within said rim.

WALTER J. GLEISNER.
